UNITED STATES PATENT OFFICE.

CHARLES L. BELLAMY, OF ARLINGTON, NEW JERSEY.

MANUFACTURE OF KNIFE-BLADES.

SPECIFICATION forming part of Letters Patent No. 319,442, dated June 9, 1885.

Application filed April 25, 1884. (No model.)

To all whom it may concern:

Be it known that I, CHARLES L. BELLAMY, of Arlington, Hudson county, New Jersey, have invented certain new and useful Improvements in the Manufacture of Knife-Blades, of which the following is a specification.

My invention relates more especially to the manufacture of blades for ordinary table-knives, but may, of course, be applied to the manufacture of blades for other cutlery.

The main object of my invention is to enable knife-blades to be rapidly and cheaply made from sheet-steel in a perfect form without the necessity of the expensive hand forging of each blade, as is now employed in the manufacture of properly-formed blades.

It is well known that it is considered an essential that all properly-formed knife-blades should have a tapering or wedging cross-section, tapering from the back to the edge, and that heretofore this has been obtained only by the operation of forging or by grinding, the former being expensive in labor, and the latter wasteful of material. It has therefore been often sought to obtain steel rolled in long thin strips with a wedging cross-section suitable to knife-blades, whereby the blades may be readily produced by cutting off sections of the bar and finishing these sections; but the difficulty or impossibility of producing bars in this shape which would be straight and not curled up has rendered this idea impracticable. According to my invention, however, I produce knife-blades of true wedging form from sheet-steel by the simple operations of cutting and rolling, without appreciable waste of material and without the necessity of expensive forging; and this result I accomplish by first cutting the blade-blank from a sheet of steel of proper width and thickness in a curved or curled form, and then passing this curved piece between beveled rollers, or rather rolls with grooves of a wedging shape, which rollers roll the strip thin or displace the metal on the concave side of the curved strip, thus stretching the metal sufficiently on that side to neutralize the curves and thus straighten the curved strip at the same time that it forms it with a wedging cross-section; and my invention consists, mainly, in the features here outlined, as hereinafter fully set forth.

In the drawings annexed, Figure 1 presents a perspective plan view of the blade-blank as it appears cut from the sheet-steel and before 55 rolling. Fig. 2 is a plan view of a sheet from which the blanks are cut. Fig. 3 is a cross-section of one of the aforesaid blanks. Fig. 4 is a front elevation of a pair of rollers for reducing the blanks to the form of straight 6c blades of wedging form. Fig. 5 is a plan view of the blade or blank after being passed through the rollers, and Fig. 6 is a cross-section thereof.

Referring to Figs. 1 and 2, *a* indicates the blade-blank as it is cut from the sheet of 65 steel, and *b* indicates the sheet from which the blanks are cut. The steel sheet *b* is flat and of uniform thickness, as shown, and of a width equal to the length of the blanks. The blanks, as shown, are cut in a curved 70 form, the convex curved side corresponding to the back edge of the finished blade, while the concave side corresponds to the cutting-side of the blade, and these curves have a definite relation or proportion to the width of the 75 blank, its thickness of metal, and the wedging form of the finished blade, so that when the blank is rolled and the concave edge thinned out the curves will be neutralized and the blank straightened out, as shown in Fig. 5. 80 These curves are therefore determined either by calculation or experiment, and will of course vary for different sizes and kinds of blades, and no specific directions for laying out the curves are therefore given here, as it 85 is the function of the experienced metal-worker to determine this in each case. I prefer, however, to have the concave and convex curves of the blade parallel, as shown, so that the blanks can therefore be cut transversely 90 from the sheet *b* in direct succession without waste, as indicated by dotted lines in Fig. 2.

The blanks, as shown best in Fig. 1, are cut with a narrow tongue, *c*, at one end, which forms the tang of the finished blade, and the 95 small pieces cut from the blank on each side of this tang (see the dotted lines in Fig. 2) form the only waste in the operation of cutting, as will be readily understood.

The blanks when cut, as seen in Fig. 1, are 100 of course of uniform thickness, as shown in Fig. 3, and they are then passed through the rollers *d d*, (shown in Fig. 4,) which reduces the thickness on one side. These rollers are

formed with wide and shallow beveled or inclined grooves *ff*, the coincidence of which present an opening of wedging form, as illustrated, corresponding to the cross-section of the knife-blade, as seen in Fig. 6, and the grooves are so proportioned to the blank that the area of the said wedging opening is about equal to the cross-section of the blade-blank, as seen in Fig. 3.

10 The rollers *d d* are of course mounted and operated in the same manner as rollers generally for rolling metal, and the curved blade-blanks *a* are passed between the grooved faces of the rollers with the concave edge of the blank on the shallow side of the groove. The action of the rollers on the blank will therefore be to compress and displace the metal on the concave side of the blank, so as to thin the blank laterally and stretch it longitudinally, 20 so that when it has passed through the rollers the blank will have become straightened out longitudinally, as seen in Fig. 5, and with a tapering or wedging form in cross-section, as seen in Fig. 6, while the top end of the blade 25 will be pointed, as seen in Fig. 5, thus producing from sheet-steel, without waste and without forging, a blade-blank of proper wedging form, which is an important improvement in the manufacture of knife-blades. This rolling operation may be performed while the 30 blanks are heated to a cherry red, if desired, but it can be performed with perfect success with the blanks cold, which is a most important advantage of this system, and will avoid the expense of heating and the scale which results therefrom, and enable the blades to be finished more readily.

After the blanks are rolled, as in Fig. 5, they are finished by grinding the top of the 40 blade to the proper shape, and also grinding or filing the tang end of the blade to properly fit the blade to the handle, after which the blanks are tempered, and after the tempering the cutting-edge of the blade is ground or 45 sharpened to the desired acuteness, and the blades are finally polished, and are then finished and ready to be attached to the handles, thus rendering the manufacture of the blades very simple and rapid from the first operation 50 to the last, and of such a nature that it may all be performed by machinery without skilled labor, thereby rendering my invention a valuable improvement in the manufacture of cutlery.

55 It will be readily noted that as the metal is compactly rolled along the thin or cutting edge of the blade, the finished blade will possess a cutting-edge of much better quality than usual, on account of the density and strength 60 of metal therein, which will enable the blade to take a much keener edge than usual, and

the knife to retain its keenness longer than would otherwise be the case, thus producing a knife of superior cutting qualities.

In the system of blade manufacture shown 65 it may not be always essential to cut the blanks at first in a curved form, and hence I do not wish to limit myself to this operation, as it may be possible to cut the blanks straight, and if they become curved after the rolling 70 operation they may be straightened by some other operation, and still the process which I set forth will be substantially the same—viz., cutting the blade-blanks from sheet metal of uniform thickness, rolling these blanks between beveled rollers so as to compress the metal in the cutting-edge of the blanks, which will secure the important advantages already set forth.

The same advantage will also be secured if 80 the blade-blanks are produced from long, straight, flat, and thin bars by cutting said bars transversely into sections of the right length, which may be subsequently curved longitudinally by a suitable operation, and 85 then rolled to produce the straightened and beveled blade, with the same effect as if the bar were originally cut curved from a sheet of steel, as in the preferred method. The preferred method is, however, considered much 90 better and cheaper than any of the modifications suggested.

What I claim as my invention is—

1. The mode of manufacturing knife-blades, consisting in first cutting the blade-blanks 95 from sheet metal of uniform thickness, then passing the blanks between rollers so as to impart a wedging form to the blank and compress the metal along the cutting-edge of the blade, substantially as herein set forth.

100 2. The mode of manufacturing knife-blades herein set forth, consisting in first forming the blade-blanks in a longitudinally-curved form, thence passing this blank longitudinally between inclined or beveled rollers having a 105 wedging coincidence, so as to reduce the concave edge of the blank, and thereby straighten the blank and impart a wedging cross-section thereto, substantially as herein shown and described.

110 3. The manufacture of knives from sheet metal without waste, consisting in forming the blade-blanks longitudinally curved, with the concave and convex sides parallel, and cutting said blanks in direct succession from 115 sheet metal, and subsequently straightening and beveling said blanks by any suitable means, substantially as herein set forth.

CHARLES L. BELLAMY.
